CLAIM

We claim the ornamental design for an optical diffuser, as shown and described.

DESCRIPTION

FIG. 1 is a front perspective view of an optical diffuser according to the invention.

FIG. 2 is a front elevation view of an optical diffuser according to the invention.

FIG. 3 is a top plan view of an optical diffuser according to the invention.

FIG. 4 is a bottom plan view of an optical diffuser according to the invention; and,

FIG. 5 is a front perspective view of an optical diffuser according to the invention as it may be used atop a light emitting diode (LED) light bulb base with heat sink.

Items shown in broken lines are for illustrative purposes only and form no part of the claimed invention.
